UNITED STATES PATENT OFFICE.

CHARLES L. A. DOEPPE, OF RICHMOND, VIRGINIA.

MACHINE FOR FRAMING FLOOR-BEAMS.

SPECIFICATION forming part of Letters Patent No. 689,169, dated December 17, 1901.

Application filed January 26, 1901. Serial No. 44,942. (No model.)

To all whom it may concern:

Be it known that I, CHARLES L. A. DOEPPE, a citizen of the United States, and a resident of Richmond, county of Henrico, and State 5 of Virginia, have invented certain new and useful Improvements in Machines for Framing Floor-Beams, of which the following is a specification.

My invention relates to framing floor-beams for railroad bridges and trestles; and it has for its object the provision of simple means whereby such floor-beams may be framed with a minimum of labor and of cost.

Floor-beams which are to be placed on rail- 15 road trestles and bridges are framed—that is, they have cut in them notches of such depth that a certain thickness of timber is left between the bottom of the notch and the opposite face of the floor-beam. The notches 20 are cut at such a distance apart that when the floor-beams are placed in position on a bridge or trestle the said notches will engage the tops of the longitudinal girders upon 25 which they are to rest. The opposite faces 30 of the floor-beams—that is, the faces to which the rails are to be subsequently spiked—will then be at a uniform height above the said girders. This framing of floor-beams for a straight track is necessary, because the floor- 35 beams, which are frequently rough-hewn, vary considerably in their thickness. When a trestle or bridge happens to be on a curve, the notches in the floor-beams must be cut to different depths, so that the said floor- 40 beams when in position may give to the outer rail its proper elevation, and also the differ- 45 ence in depth of the notches of those floor-beams which are destined for the approach to a curve must have a gradual variation as 50 the curve is approached, so that the eleva- 55 tion of the outer rail may be obtained gradu- 60 ally. Again, in cases where what are known as "easement" curves are used—that is, curves whose radius becomes shorter as their 65 center is approached, and vice versa—it is 70 necessary that the outer rail should be ele- 75 vated gradually, its highest point being in the center and its least elevation at the ends of the curve. This of course necessitates a 80 gradual raising and lowering of the outer 85 ends of the floor-beams. In framing these 90 floor-beams by hand it is necessary to care-

fully calculate the depth to which each floor-beam to be used on easement curves must be notched, and care must be taken to obtain 55 the proper difference in depth between the notches in each floor-beam and to obtain the proper increase or decrease in their difference as the center of the curve is approached and left. Consequently the correct framing 60 of floor-beams by hand is an operation attended by much labor and great cost; and the object of my invention is the provision of means whereby the correct framing of floor-beams for bridges, trestles, &c., may be ef- 65 fected with expedition and with a minimum of labor and cost.

In order to render clear the following description of my machine and its working, I will first give a brief outline of the manner in 70 which it operates to frame floor-beams. Cutters of a width necessary to cut the notches in the floor-beams are arranged at the proper distance apart on a shaft, the shaft being pro- 75 vided with means whereby it may be rapidly revolved. Circular saws are carried one on each end of the cutter-shaft, their function being to cut the floor-beam to its proper length. The floor-beam to be framed is placed upon a traveling table, which is adjustable in 80 a vertical plane in order to regulate the in- 85 clination of the floor-beam. The traveling table, and consequently the floor-beam, having been set at its required inclination, the driv- 90 ing mechanism is thrown into gear and the floor-beam is carried forward to the cutters, which, revolving, cut the required notches in it. If the floor-beam be destined for a straight piece of track, the traveling table is set so that 95 its upper surface is horizontal. Consequently the bottoms of the notches cut in the floor- 100 beams will be equidistant from the face of the said floor-beams, for the said face upon which the rails are to be laid is placed downward in the machine and will therefore have the same inclination as the upper face of the traveling table. While the cutters are notching the floor-beams the circular saws will be cutting off the crop ends. Should the bridge or trestle on which the floor-beams are to be used form 105 a part of a curve, it will be necessary to cut the notches in each floor-beam to different depths in order to obtain the proper elevation of the outer rail. To do this, the traveling

table, which carries the floor-beams, is set to the required inclination, and consequently all floor-beams notched with the table at this inclination will have notches of the required difference in depth. Again, should the bridge or trestle on which the floor-beams are to be used form an approach to a curve or form an easement curve or a part of one it will be necessary to make the difference in depth of the notches in the floor-beams vary as the approach or the curve progresses. To obtain the variation in the case of an approach, the inclination of the traveling table is increased for each floor-beam, or, if this is considered unnecessary, for every few floor-beams, until the floor-beams have received the proper inclination to give to the outer rail its proper elevation, and in the case of easement curves the inclination of the table, and consequently the inclination of the floor-beams, is increased and decreased as the center of the curve is approached and left.

Referring to the drawings which accompany and form a part of this specification, and in which like numerals refer to like parts in the different views, Figures I, II, and III are views of the machine in front elevation, plan, and side elevation, respectively. Fig. IV is a vertical section of the machine. Fig. V is a detail of the reversing-gear. Fig. VI is a detail, partly in section, of the table-inclining mechanism. Fig. VII is a detail in section of the adjustable heads for carrying the cutter-shaft; and Fig. VIII is a view of the machine in front elevation, showing a modified arrangement of the adjustable traveling table.

In Figs. I, II, III, and IV, 11 are guide-beds having guides 22. Supported by the guides and movable thereon is the table 3, which is provided with brackets 44, having bearings 55. 6 is a table provided with trunnions 77, which trunnions engage in the bearings 55, and so form a pivot on which the table 6 may be swung. The floor-beam to be framed is slid endwise onto the table 6, rollers 88, &c., being let into the said table in order to facilitate the placing of the floor-beams thereon. 99 are lugs provided with projecting points 1010, by means of which and the movable clamp 11 the floor-beam may be held in position on the table 6. The clamp 11 is attached to a threaded spindle 12, which engages in a female screw cut through the center of one of the trunnions 7, the threads of the spindle 12 and of the female screw being what are termed "interrupted" threads, so that when a floor-beam has been placed in position the clamp 11 may be quickly brought to bear against it and be caused to clamp it by a turn of the spindle 12 through a small arc. 13 is a handle by means of which the spindle 12 may be rotated.

In Figs. I, II, and III, 14 represents a floor-beam in position to be framed, and in Fig. IV, 14 represents the same floor-beam after it has been framed, the bottom of one of the

notches being indicated by the dotted line at 15. 16 is the cutter and saw shaft, which is mounted in adjustable heads 171717, which are carried by the standards 181818. Upon the shaft 16 are mounted the saws 1919, the cutters 2020, and the pulleys 2121, through which, being driven and being connected by means of belts with the driving-pulleys of some motor, the shaft 16, with its cutters and saws, is revolved. The saws 1919 are set at such a distance apart that they will cut the floor-beam to the required length, and the cutters 2020 are spaced so that the notches cut by them in the floor-beam may be at the correct distance apart. The cutters may be of any of the common forms designed to cut a slot or notch of uniform depth, those shown in the drawings (see Fig. III) being provided with saw-sections 2222, which saw-sections cut two narrow saw-slots in the floor-beam at a distance apart equal to the width of the desired notch and being also provided with cutting-blades 2323, which cut out the material between the saw-slots cut by the saw-sections 2222. The cutter-blades may be plain if the bottoms of the notches are to be plain, or they may have projecting portions if grooves are to be cut in the bottoms of the notches in the floor-beams to allow for rivet-heads, &c.

The table 6 is adjusted as to its inclination by means of gearing attached, preferably, to the lower side of the table 3, where it will be out of the way and where it will not be liable to damage from falling timber. To the lower side of the adjustable table 6 is pivoted the rod 24, on the lower end of which are cut screw-threads. This rod 24 passes through the table 3, and its threaded part engages in a female screw cut through the body of the bevel-wheel 25, which is supported on the under side of the table 3 by means of the bracket 26. (See Fig. VI.) Gearing with the bevel-wheel 25 is another bevel-wheel 27, mounted on the shaft 28, which is carried in brackets 2929, attached to the table 3. On the shaft 28 there is also mounted a hand-wheel 30, by means of which the shaft 28, and consequently the bevel-gear 27, may be rotated. It will be seen that upon rotating the shaft 28 the bevel-gear 27 will rotate the bevel-gear 25, and the latter gear will, according to the direction in which it is revolved, raise or lower the rod 24, the threaded part of which engages threads cut through the body of the said bevel-gear, and it will consequently raise or lower that end of the table 6 to which the rod 24 is pivoted. The extent to which the rod 24 is raised or lowered—that is, the extent to which the table 6 is inclined upon turning the shaft 28—is preferably indicated by means of a graduated gage-rod 31, attached to the lower side of the table 6 and which enters a slot 32 cut to receive it in the table 3. Upon this gage-rod may be cut marks, the relation of which to the surface of the table 3 will indicate the degree of inclination of the table 6.

A floor-beam having been clamped in position upon the table 6, the latter is set so that the notches to be cut in the beam shall have the required difference in depth, or so 5 that they shall be of equal depth—that is to say, the table is given the required inclination or is set in a horizontal position. This having been done, the table 3, carrying the table 6 and the floor-beam, is caused to slide 10 along the guides 22, and so carry the floor-beam into engagement with the saws 19 and cutters 20. As soon as the beam has been carried so far that the crop ends have been cut off and the notches have been cut the table 3 is caused to recede, and so bring the beam out 15 of engagement with the saws and cutters. Suppose that the beams which we are about to frame are intended for a straight trestle or bridge. We set the table 6 in a horizontal position. The bottoms of the notches cut will then be equidistant from the face of the beam—that is, from what is now the lower side of the beam. If the beams are intended for an ordinary 20 curve, the table 6 is given such an inclination that the notches cut will have the difference in depth required to give to the outer rail of the curve its proper elevation, and every beam required for use on the curve can be correctly notched without resetting the table 25 6. No measurements need be made on any of the beams. No "laying off" is necessary. All that is necessary is first to set the table 6 to the inclination required to give the proper difference in depth to the notches, the 30 inclination to be indicated by the gage 31, and then to place the required number of beams successively upon the table 6 and pass them under the cutters and saws. If floor-beams are now to be framed for the approach to an 35 ordinary curve or for an easement curve—that is to say, if floor-beams are to be so framed that the difference in depth of the notches in each beam shall steadily increase as the ordinary curve or as the center of the 40 easement curve is approached and decrease as they are left—the first beam will have notches whose bottoms are equidistant from the face of the beam, (it being understood that by "the face of the beam" the face 45 which is lowest while the beam is on the table 6 is referred to, and the surface on which the notches are cut is the true bottom of the beam,) and the beam destined for the commencement of the ordinary curve or for the 50 center of the easement curve will have notches between whose depths there will be the greatest difference. Suppose that it is required to frame one hundred beams for an approach to an ordinary curve and that the elevation of the outer rail of the curve is to be one inch. The difference in depth between the notches of the beam will increase by approximately one one-hundredth of an inch as the approach progresses. Therefore for the first 55 beam to be framed we set the table 6 in a horizontal position, for the second at such an inclination that there will be a difference of one

one-hundredth of an inch in depth between the two notches, for the third a difference of one-fiftieth of an inch, for the fourth a difference of three one-hundredths of an inch, and so on. In practice this would probably be considered too fine an adjustment, and a given number of beams—say five—would be so framed that the difference in the notches of 75 each would be one-twentieth of an inch, the difference in the notches of the next five beams one-tenth of an inch, of the next five three-tenths, of the next five one-fifth, and so on. 80

In Fig. I the table 6 is shown pivoted at its center. If the depth of the two notches cut in a beam when the table 6 is horizontal is three-quarters of an inch and if now the table 6 be so inclined that the difference in 85 depth of the notches cut in the next beam is half an inch, one of the said notches will be one inch in depth and the other half an inch—that is to say, the depth of one notch will be increased and the depth of the other decreased by a quarter of an inch. That is equivalent to saying that while we elevate one rail we lower the other an equal amount. By doing so we give to the outer rail the required elevation over the inner one without 90 changing the height of the center of the track. This is considered by some engineers a very important and desirable advantage, as a train running on such a track is not required to "climb," the center line of the train always 95 remaining in the same horizontal plane. It will be readily seen that to frame beams by hand for such a track would entail a great amount of labor and cost, as after the necessary calculations had been made each beam 100 would have to be carefully gaged and marked off before being framed. If it be desired to so frame the floor-beams that in obtaining the required elevation of the outer rail the said outer rail only is moved from its original horizontal plane—that is, so that the inner or lower rail is kept in the same horizontal plane throughout the approach or curve—the table 6 of the machine is pivoted at a point in a vertical line with one of the cutters 20 instead of at a point situated at its own center. The machine with the table 6 so pivoted is shown in Fig. VIII, wherein the trunnions attached to the table 6, one of which trunnions is indicated in Fig. VIII by the numeral 7, are in a vertical line with one of the cutters 20. The clamp 11, spindle 12, and other parts of the machine are preferably retained in the positions in which they are shown to be in Fig. I. If the notches in the beams are 115 not cut at a distance apart equal to the gage of the track, but at a greater distance apart, as is usually the case, the pivot 33 is arranged to fall in the same vertical plane as that point on the beam at which the inner or immovable rail will be located. Thence no matter at 120 what inclination the beams are framed that point on the beams at which the rail will be located will when the beams are placed in 125 130

position always lie in the same horizontal plane.

As the beams used in some cases are thicker than those used in others, it is necessary that we should be able to adjust the position of the beams to be framed relatively to the position of the cutters, so that the required amount of timber may be left between the bottoms of the notches and the faces of the beams. This adjustment may be attained by adjusting either the cutter-shaft or the beam-support vertically. The simplest manner in which we could adjust the latter would be by providing means for vertically adjusting the guides 2 2 or the guide-beds 1 1, to which all mechanisms for operating the tables 3 and 6 would be attached. It has been found that this method of attaining the required adjustment is attended with some objections, and I therefore adopt the former method of making the cutter-shaft 16 vertically adjustable. Owing to the fact that it is most desirable to have cutters of as small a diameter as possible, for the greater the diameter of the cutters the greater is the power required to drive them when in operation, it is necessary to so arrange the heads 17 and the adjustable shaft-bearings which they carry that as much head room as possible may be obtained beneath them to allow the beams being framed to pass without fouling. The usual forms of adjustable shaft-bearings are not available, for those which allow sufficient head room take too long to set and others, which can be quickly set, do not allow the required head room. I have therefore devised a special means for adjusting the shaft-bearings, which means allow the necessary head room and which can be quickly set.

In Figs. I, II, III, IV, VII, and VIII, 34 34 34 are casings, open on one side and at the top and bottom, which are bolted to the flanges 35 of the standards 18 18 18, the open side of the casings being next to the said flanges. Consequently these casings form with the said flanges boxes having neither top nor bottom, and inside these boxes are suspended the shaft-bearings, the walls of the boxes forming guides for the latter. In opposite sides of the casings there are cut openings 36 (see Figs. III and IV) to allow the shaft 16 to pass through. Referring to Fig. VII, 37 is a yoke which carries the brasses 38 38 and which is provided with the threaded spindle 39, the threads of which spindle engage in threads cut in the hub of the hand-wheel 40. The hand-wheel 40 rests upon the top of the cover 41, through which cover a hole is cut for the passage of the spindle 39. It will be seen that upon revolving the hand-wheel 40 the yoke 37, carrying the brasses 38 38, will be caused to rise or descend according to the direction in which the hand-wheel is revolved. In order to keep the upper brass 38 in position and bearing on the shaft 16, a pin 42 is passed down the center of the spindle 39, and it is caused to bear upon a plate of hard metal 43, which is placed

upon the top of the upper one of the brasses 38. The upper end of the pin 42, which is threaded, engages in a female screw 44, cut in the upper end of the yoke-spindle 39, and it is provided with a square head, to which may be fitted a wrench or handle for turning the screw. To adjust the shaft 16 to a new position, it is only necessary to give to the three hand-wheels on the three heads revolutions through arcs of equal magnitude.

Having described the manner in which the cutters 20, the saws 19, and the table mechanisms operate, I will explain the manner in which the floor-beams are advanced to the cutters and saws.

Carried in the brackets 45 45, attached to the guide-beds 1 1, there are shafts 46 46, having cut on them screw-threads, which threads engage in female-threaded lugs 47 47, secured to the under side of the table 3. Keyed one on each of the shafts 46 46 are worm-wheels 48 48, which worm-wheels gear with worms 49 49, carried on the shaft 50, which shaft is carried in brackets 51 51 51, attached to the standards 18 18 18. Secured in the shaft 50 are the clutch mechanisms 52 52, which are arranged to engage in loose pulleys 53 54. The loose pulleys are driven by means of belts 95 leading from the motor, one belt being crossed, so that the pulleys 53 54 may be given motions in directions opposite to one another. These directions of motion are indicated by means of arrows in Fig. II. In Figs. II, IV, and V, 100 55 55 are bell-crank pivoted on one of the standards 18 and connected with the clutch-levers 56 56. The bell-crank 55 55 are operated by means of rods 57 58 to throw the clutches in and out of gear, and the rods in 105 their turn are actuated by means of lugs 59, 60, and 61, attached to the table 3 and which are arranged to strike stops 62, 63, and 64 when the table is in motion, the stop 62 being attached to the rod 57 and the stops 63 110 and 64 to the rod 58. (See Fig. IV.) The manner in which this mechanism operates the table 3 is as follows: The table being in the position shown in Figs. II and III and a beam having been placed in position on the table 6 115 and the said table properly adjusted, the pulley 53, which we will suppose is driven by the straight belt, is thrown into gear with its clutch mechanism by pulling the rod 57 by hand in the direction indicated by the arrows. 120 The worm-shaft 50, the worm-gearings, and the screw-shafts 46 46 are at once set in motion. The screw-shafts, revolving in the direction indicated by the arrows and acting on the female-threaded lugs 47 47, draw the table 3 forward, and consequently draw the beam to be framed into engagement with the cutters and saws. Just after the operation of cutting the notches in the beam and of sawing off the crop ends has been completed 130 the lug 59 (see Fig. V) strikes the stop 62 on the rod 57 and, throwing the said rod back to its original position, throws the pulley 53 out of engagement with its clutch mechanism,

and so checks the forward movement of the beam. At the same time the lug 60 (see Figs. IV and V) strikes the stop 63, attached to the rod 58, and so throws the pulley 54 (which is driven by the cross-belt) and its clutch mechanism into gear. The pulley 54 imparts to the shaft 50 and the screw-shafts 46, 46 motions contrary in direction to those which were imparted to them by the pulley 53, and consequently the tables 3 and 6 and the beam are now caused to recede from the cutters and saws. Just as the tables near their first position the lug 61 strikes the stop 64, attached to the rod 58, and, throwing the latter in the direction indicated by the arrow, (see Fig. IV,) throws the pulley 54 out of gear with its clutch mechanism. Both of the pulleys 53 and 54 are now free from their clutch mechanisms, and the tables and beam consequently come to rest. The framed beam can now be removed and another placed in position.

Having now described my invention, what I claim, and desire to protect by Letters Patent of the United States, is—

1. In a machine of the character described, the combination of standards for carrying a cutter-shaft, vertically-adjustable bearings attached to the standards, a rotatable shaft 30 mounted in the bearings, means for revolving the shaft, rotary cutters mounted on the shaft one adjacent to each end thereof, guideways, a carrier adapted to reciprocate upon the guideways, a table for supporting the beam pivoted at the middle of its length to the carrier so as to be adjustable as to its inclination in a vertical plane parallel to the cutter-shaft, means for adjusting the inclination of the table, and means for reciprocating the 40 carrier intermittently on the guideways to carry the beam into and out of engagement with the cutters.

2. In a machine of the character described, the combination of standards for carrying a cutter-shaft, vertically-adjustable bearings attached to the standards, a rotatable shaft mounted in the bearings, means for revolving the shaft, rotary cutters mounted on the shaft one adjacent to each end thereof, guideways, 50 a carrier adapted to reciprocate upon the guideways, a table for supporting the beam pivoted to the carrier so as to be adjustable as to its inclination in a vertical plane parallel to the cutter-shaft, means for adjusting the inclination of the table, and automatic means for reciprocating the carrier intermittently on the guideways to carry the beam into and out of engagement with the cutters.

3. In a machine of the character described, the combination of standards for carrying a cutter-shaft, vertically-adjustable bearings attached to the standards, a rotatable shaft mounted in the bearings, means for revolving the shaft, rotary cutters mounted on the shaft 60 one adjacent to each end thereof, guideways, a carrier adapted to reciprocate upon the guideways, a table for supporting the beam

pivoted to the carrier at the middle of its length so as to be adjustable as to its inclination in a vertical plane parallel to the cutter-shaft, means for adjusting the inclination of the table, and automatic means for reciprocating the carrier intermittently on the guideways to carry the beam into and out of engagement with the cutters. 75

4. In a machine of the character described, the combination of standards for carrying a cutter-shaft, vertically-adjustable bearings attached to the standards, a rotatable shaft mounted in the bearings, means for revolving the shaft, rotary cutters mounted on the shaft one adjacent to each end thereof, guideways, a carrier adapted to reciprocate upon the guideways, a table for supporting the beam pivoted to the carrier so as to be adjustable as to its inclination in a vertical plane parallel to the cutter-shaft, means for adjusting the inclination of the table, endless screw-shafts engaging in threaded lugs attached to the carrier, a drive-shaft, means connecting the drive-shaft with the endless screw-shafts whereby the drive-shaft may rotate the endless screw-shafts to reciprocate the carrier, and means for intermittently operating the drive-shaft. 90

5. In a machine of the character described, the combination of standards for carrying a cutter-shaft, vertically-adjustable bearings attached to the standards, a rotatable shaft mounted in the bearings, means for revolving the shaft, rotary cutters mounted on the shaft one adjacent to each end thereof, guideways, a carrier adapted to reciprocate upon the guideways, a table for supporting the beam pivoted at the middle of its length to the carrier so as to be adjustable as to its inclination in a vertical plane parallel to the cutter-shaft, means for adjusting the inclination of the table, endless screw-shafts engaging in threaded lugs attached to the carrier, a drive-shaft, means connecting the drive-shaft with the endless screw-shafts whereby the drive-shaft may rotate the endless screw-shafts to reciprocate the carrier, and means for intermittently operating the drive-shaft. 105

6. In a machine of the character described, the combination of standards for carrying a cutter-shaft, vertically-adjustable bearings attached to the standards, a rotatable shaft mounted in the bearings, means for revolving the shaft, rotary cutters mounted on the shaft one adjacent to each end thereof, guideways, a carrier adapted to reciprocate upon the guideways, a table for supporting the beam pivoted to the carrier so as to be 110

adjustable as to its inclination in a vertical plane parallel to the cutter-shaft, means for adjusting the inclination of the table, endless screw-shafts engaging in threaded lugs attached to the carrier, a drive-shaft, means connecting the drive-shaft with the endless screw-shafts whereby the drive-shaft may rotate the endless screw-shafts to reciprocate the carrier, means for setting the drive-shaft 125

in motion in one direction to bring the beam into engagement with the cutters, means for automatically reversing the motion of the drive-shaft to bring the beam out of engagement with the cutters, and means for automatically throwing the drive-shaft out of gear to bring the beam to rest.

7. In a machine of the character described, the combination of standards for carrying a cutter-shaft, vertically-adjustable bearings attached to the standards, a rotatable shaft mounted in the bearings, means for revolving the shaft, rotary cutters mounted on the shaft one adjacent to each end thereof, guideways, a carrier adapted to reciprocate upon the guideways, a table for supporting the beam pivoted at the middle of its length to the carrier so as to be adjustable as to its inclination in a vertical plane parallel to the cutter-shaft, means for adjusting the inclination of the table, endless screw-shafts engaging in threaded lugs attached to the carrier, a drive-shaft, means connecting the drive-shaft with the endless screw-shafts whereby the drive-shaft may rotate the endless screw-shafts to reciprocate the carrier, means for setting the drive-shaft in motion in one direction to bring the beam into engagement with the cutters, means for automatically reversing the motion of the drive-shaft to bring the beam out of engagement with the cutters, and means for automatically throwing the drive-shaft out of gear to bring the beam to rest.

8. In a machine of the character described, the combination of standards for carrying a cutter-shaft, vertically-adjustable bearings attached to the standards, a rotatable shaft mounted in the bearings, means for revolving the shaft, rotary cutters mounted on the shaft one adjacent to each end thereof, guideways, a carrier adapted to reciprocate upon the guideways, a table for supporting the beam pivoted to the carrier so as to be adjustable as to its inclination in a vertical plane parallel to the cutter-shaft, means for adjusting the inclination of the table, endless screw-shafts engaging in threaded lugs attached to the carrier, a drive-shaft, means connecting the drive-shaft with the endless screw-shafts whereby the drive-shaft may rotate the endless screw-shafts to reciprocate the carrier, a friction-pulley 53 by which the drive-shaft is revolved to move the carrier forward, means for throwing said pulley into gear, a friction-pulley 54 by which the drive-shaft is revolved to reverse the motion of the carrier, means for throwing the pulley 53 out of gear and the pulley 54 into gear simultaneously, and means for throwing the pulley 54 out of gear to bring the carrier to rest.

9. In a machine of the character described, the combination of standards, vertically-adjustable bearings attached to the standards, a revolute shaft mounted in the bearings, cutters mounted on the shaft one adjacent to each end thereof, circular saws mounted one

at each end of the shaft, means for revolving the shaft, a carrier provided with and adapted to reciprocate upon guideways, a table for supporting the beam pivoted to the carrier so as to be adjustable as to its inclination in a vertical plane parallel to the cutter-shaft, means for adjusting the inclination of the table, endless screw-shafts engaging in threaded lugs attached to the carrier, a drive-shaft, means connecting the drive-shaft with the endless screw-shafts whereby the drive-shaft may rotate the endless screw-shafts to reciprocate the carrier, and means for intermittently operating the drive-shaft.

10. In a machine of the character described, the combination of revoluble cutters adapted to notch the beam, means for revolving the cutters, guideways, a carrier adapted to reciprocate upon the guideways, a table for supporting the beam pivoted at the middle of its length to the carrier so as to be adjustable as to its inclination in a vertical plane parallel to the cutter-shaft, means for adjusting the inclination of the table, automatic means to slide the carrier forward to carry the beam into engagement with the cutters, to reverse the motion of the carrier to carry the beam out of engagement with the cutters, and to bring the beam to rest.

11. In a machine of the character described, the combination of a revoluble shaft, means for revolving the shaft, rotary cutters mounted on the shaft one adjacent to each end thereof, circular saws mounted on the shaft one at each end thereof, guideways, a carrier adapted to reciprocate upon the guideways, a table for supporting the beam pivoted at the middle of its length to the carrier so as to be adjustable as to its inclination in a vertical plane parallel to the cutter-shaft, means for adjusting the inclination of the table, and automatic means for intermittently reciprocating the carrier to carry the beam into and out of engagement with the cutters and saws.

12. In a machine of the character described, the combination of a revoluble shaft, cutters mounted on the shaft one adjacent to each end thereof, means for revolving the shaft, guideways, a carrier adapted to reciprocate upon the guideways, a table for supporting the beam and pivoted to the carrier so as to be adjustable in a vertical plane, and automatic means for intermittently reciprocating the carrier to carry the beam into and out of engagement with the cutters.

13. In a machine of the character described, the combination of standards for carrying a cutter-shaft, a cutter-shaft, means for revolving the cutter-shaft, rotary cutters mounted on the shaft one adjacent to each end thereof, guideways, a carrier adapted to reciprocate upon the guideways, a table for supporting the beam pivoted to the carrier so as to be adjustable as to its inclination in a vertical plane parallel to the cutter-shaft, means for adjusting the inclination of the table, endless screw-shafts engaging in threaded lugs at-

tached to the carrier, a drive-shaft, means connecting the drive-shaft with the endless screw-shafts whereby the drive-shaft may rotate the endless screw-shafts to reciprocate the carrier, and means for intermittently operating the drive-shaft.

14. In a machine of the character described, the combination of standards for carrying a cutter-shaft, a cutter-shaft, means for revolving the cutter-shaft, rotary cutters mounted on the shaft, one adjacent to each end thereof, guideways, a carrier adapted to reciprocate upon the guideways, a table for supporting the beam pivoted at the middle of its length to the carrier so as to be adjustable as to its inclination in a vertical plane parallel to the cutter-shaft, means for adjusting the inclination of the table, endless screw-shafts engaging in threaded lugs attached to the carrier, a drive-shaft, means connecting the drive-shaft with the endless screw-shafts whereby the drive-shaft may rotate the endless screw-shafts to reciprocate the carrier, and means for intermittently operating the drive-shaft.

15. In a machine of the character described, the combination of a revolute shaft, means for revolving the shaft, rotary cutters mounted on the shaft one adjacent to each end thereof, guideways, a carrier adapted to re-

ciprocate upon the guideways, a table for supporting the beam pivoted at the middle of its length to the carrier so as to be adjustable as to its inclination in a vertical plane parallel to the cutter-shaft, means for adjusting the inclination of the table, and automatic means for reciprocating the carrier to carry the beam into and out of engagement with the cutters.

16. In a machine of the character described, the combination of a revolute shaft, means for revolving the shaft, rotary cutters mounted on the shaft one adjacent to each end thereof, guideways, a carrier adapted to reciprocate upon the guideways, a table for supporting the beam pivoted to the carrier so as to be adjustable as to its inclination in a vertical plane parallel to the cutter-shaft, means for adjusting the inclination of the table, and automatic means for reciprocating the carrier to carry the beam into and out of engagement with the cutter.

Signed at Richmond, in the county of Henrico and State of Virginia, this 19th day of December, A. D. 1900.

CHARLES L. A. DOEPPE.
